(57) **CLAIM**

The ornamental design for a focus vision cap, as shown and described.

DESCRIPTION

FIG. 1 is a perspective view of a focus vision cap showing my new design;

FIG. 2 is a right side elevational view, the opposite side being a mirror image;

FIG. 3 is a top plan view;

FIG. 4 is a front elevational view;

FIG. 5 is a rear elevational view;

FIG. 6 is a bottom plan view; and,

FIG. 7 is a left side elevational view.

The user's head shown in broken lines in FIGS. 1 and 7 is for illustrative purposes only and forms no part of the claimed design. The broken lines on the bill of the hat represent stitching which forms part of the claimed design.
